(57) CLAIM

The ornamental design for a handbag as shown and described.

DESCRIPTION

FIG. 1 is a front perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged partial view of a portion of the handbag as indicated in FIG. 1; and,

FIG. 9 is an enlarged partial view of another portion of the handbag as indicated in FIG. 2.

The broken lines encircling unshaded features depict portions of the handbag and form no part of the claim. The darker dashed broken lines crossing claimed surfaces depict claimed stitching. The rectangles shown in broken lines in FIGS. 1, 2, 8, and 9 depict the cut lines of the enlarged views and form no part of the claim.
